[57] CLAIM

The ornamental design for a miniature decorative vase, as shown and described.

DESCRIPTION

FIG. 1 is a front view of a miniature decorative vase showing my new design.

FIG. 2 is a side view of the miniature decorative vase shown in FIG. 1, the opposite side being mirror image.

FIG. 3 is a back view of the miniature decorative vase shown in FIG. 1.

FIG. 4 is a top view of the miniature decorative vase shown in FIG. 1.

FIG. 5 is a bottom view of the miniature decorative vase shown in FIG. 1; and,

FIG. 6 is a cross sectional view taken along line 6—6 in FIG. 3.

The area within the broken lines as well as the broken lines shown in FIGS. 1 and 2 forms no part of the claimed design.
